DAVID BRUCE, OF NEWTOWN, NEW YORK.

Design No. 2,618, dated April 16, 1867.

DESIGN FOR PRINTERS' TYPE.

The Schedule referred to in these Letters Patent and making part of the same.

TO ALL WHOM IT MAY CONCERN:

Be it known that I, DAVID BRUCE, of Newtown, Queens county, State of New York, have invented or produced a new and original Design for Letter-Press Type, which I have named or designated as the "Rim-Shaded Gothic Script;" and I do hereby declare that the following is a full description of the same.

The nature of my invention consists in combining with the printers' type known to the trade as the Gothic script letter or character, a rim or marginal hair line, projecting in perspective so as to give to the letter a relief to the body of it, though not in heavy shading, according to the theory of lights and shadows, and thereby not only producing a new style of type, but at the same time a very pleasing effect upon the observer. But to describe my invention more particularly, I will refer to the accompanying drawings or specimens of the printing of the "Rim-Shaded Gothic Script," forming a part of this specification, the same letters of reference wherever they occur referring to like parts.

Letter a represents the ordinary letter or character of the "Gothic" alphabet and numerals, having a delicate marginal outline or rim, b, entirely around the body of the letter, forming what may be called a letter within a letter, but with the peculiarity of the outlined letter or rim being somewhat larger than the body of the letter, and nearly touching the upper and left-hand sides of it, as seen at c, and projecting in perspective beyond the lower and right-hand side of the body of the letter, as seen at b, so as to give the appearance of a shaded letter, or a letter in relief from the solid heavy lines of a Gothic letter.

What I claim, therefore, is—

The design for the new style of Gothic type, which I have designated as the "Rim-Shaded Gothic Script or Text," as hereinbefore set forth and shown.
